UNITED STATES PATENT OFFICE

JAMES G. BLUNT, OF SCHENECTADY, NEW YORK

FRAME CROSS-TIE AND APPARATUS SUPPORTING STRUCTURE FOR LOCOMOTIVES

Application filed February 5, 1930. Serial No. 425,972.

This invention relates to frame cross-tie and apparatus supporting structures for locomotives, and more particularly to structures adapted to serve conjointly as a frame cross-tie between the side frames of a locomotive and a support for lateral motion device levers, piston rod cross head guides, a reverse shaft, valve motion members, and boiler waist plates.

10 An object of the present invention is to provide a combined frame cross-tie and apparatus supporting structure which may be fabricated of a plurality of parts or formed as an integral casting, and which will more efficiently cross brace a pair of side frames, and more efficiently support the apparatus indicated, than the independent cross-ties and apparatus supports heretofore employed.

20 A further object of the invention is to provide a combined frame cross-tie and apparatus supporting structure, whereby a substantial number of the machining operations and bolts required by the practices heretofore known, are eliminated.

Other objects of the invention will herein-after readily appear.

The improvement claimed is hereinafter fully set forth.

30 In the accompanying drawings: Figure 1 is a side view in elevation of the forward portion of a locomotive embodying the improved combined cross-tie and apparatus supporting structure; Fig. 2, an enlarged top plan view of a part of the combined cross-tie and apparatus supporting structure shown in Fig. 1; Fig. 3, a side view in elevation of the body member of the structure shown in Fig. 2; Fig. 4, a vertical longitudinal section of the body member taken on the line IV—IV of Fig. 2; Fig. 5, a view, one half in front elevation, and one half in transverse vertical section taken on the line V—V of Fig. 1; and Figs. 3a and 5a, fragmentary side and front views respectively of a modified form of front transverse beam adapted for the application of cross head guides of the Laird type.

40 In the practice of the invention, referring descriptively to the specific embodiment thereof which is herein exemplified, the com-

bined frame cross-tie and apparatus supporting structure 10, is incorporated in a locomotive comprising a pair of side frames 11, journal boxes 12, springs 13, suspension links 14, a lateral motion device 15, a reverse shaft 55 16, valve motion members 17, boiler waist plates 18, piston rod cross head guides 19, and a frame cross-tie member 20. The lateral motion device 15 is of the type disclosed in U. S. Patent No. 1,565,781, issued to me December 15, 1925, and comprises a pair of bifurcated levers 21, bearing at one end on journal boxes 12 and fulcrumed on shafts 22. The valve motion members 17, are shown as the bell-crank of the well-known Baker gear, 60 65 but it is to be understood that any type of valve motion gear may be employed.

The combined frame cross-tie and apparatus supporting structure 10 comprises a substantially H shape body member 23, 70 formed as an integral casting; a pair of valve motion supports 24, one for each valve motion member 17; a pair of bearing members 25 for the reverse shaft 16; and a pair of guide yokes 25a for supporting the piston rod crosshead guides 19. The valve motion supports 24, the reverse shaft bearing members 25, and the guide yoke 25a, are 75 shown as separately formed castings which may be fastened to the body casting 23 by bolts or other suitable means, but it is within the contemplation of the invention to cast them integral with the body member.

80 The body member comprises a longitudinal bed 26, adapted to bridge the two side frames 11, a front transverse beam 27, and a rear transverse beam 28. The transverse beams are superposed on the bed and their ends project laterally therebeyond. The 85 bed 26 is of box construction and of substantially H-shape comprising a central longitudinal fish belly beam 29; rear portions 30, one extending laterally from each side of the longitudinal beam; and front portions 31, one extending laterally, from each side of 90 the beam. Each lateral extension 30 and 31 is provided with a horizontal flange 32, a vertical flange 33, and a boss 34a, the flanges and bosses being provided with suitable 95 holes 34 for bolting the bed to the side frame 100.

members 11. Each of the lateral extensions is also provided with a pocket 35 for the reception of one of the suspension links 14.

The space between the lateral extensions 5 on each side of the longitudinal beam 29 provides a pocket 36, for a lateral motion lever 21. Each side wall 38 of each lever pocket is provided with a cylindrical socket or bearing 39 for the reception of one end of one 10 of the fulcrum shafts 22, and the rear wall of each pocket is formed with a stop boss 40 for limiting movement of the lever.

The front of the bed is formed with a transverse vertical flange 41, having bolt 15 holes 42 for fastening the bed to the flange 43 of the frame cross-tie member 20, which cross-tie member may be joined, if desired, to a rear extension from a cylinder saddle in accordance with well-known practice.

20 The front transverse beam 27 comprises a transverse vertical wall 44, joined at its bottom to the bed 26, two spaced transverse horizontal walls 45 joined to the vertical wall 44, and two longitudinal vertical walls 46, 25 one disposed adjacent each end of the beam and joined to the transverse vertical wall 44, and the spaced transverse horizontal walls 45. Each end of the vertical wall 44 is provided with bolt holes 47, for the attachment 30 of a guide yoke 25a for the piston rod cross-head guides 19, and the front end of one of the valve motion supports 24.

The rear transverse beam 28 comprises a transverse vertical wall 51 joined at its base 35 to the bed 26, two spaced transverse horizontal walls 52 joined to the vertical wall 51, and two longitudinal vertical walls 53, one at each end of the beam and joined to the walls 51 and 52 thereof. Each longitudinal wall 53 is provided with bolt holes 54 for the attachment of the rear end of one of the valve motion supports 24. The transverse vertical wall 51 is provided adjacent each end with a pair of rearwardly projecting spaced lugs 55 which serve as stops for limiting rotatory movement of the reverse shaft 16, a boss 56, having bolt holes 57 for the attachment of the reverse shaft bearing member 25, and bolt holes 58 for the attachment 50 of a boiler waist plate 18.

Each guide yoke 25a is provided at its top with a vertical flange 59, having bolt holes 60 for the attachment of one of the boiler waist plates 18.

55 In Figs. 3a and 5a of the drawings is shown a modified form of the front transverse beam 27 wherein the ends thereof are provided at their bottoms with a flange 61, having bolt holes 62 for the application of 60 a cross head guide of the Laird type.

While one of the preferred forms of construction has been shown, it is obvious that many variations in procedure, form, arrangement, and construction of the parts can 65 be made, and the invention is not therefore

limited to the particular embodiment disclosed, but includes such changes and modifications as come within the spirit and scope of the invention as set forth in the appended claims.

70 The invention claimed and desired to be secured by Letters Patent is:

1. A cross-tie member made as an integral casting having means for securing it to the side frame members of a locomotive and comprising a box-shaped structure having a portion narrowed transversely to provide oppositely disposed spaces, said transversely narrowed portion being thickened vertically to add strength to compensate for loss in 80 strength caused by said narrowing of the casting.

2. In a structure of the character described, the combination of a cross-tie member made as an integral casting having means for securing it to the side frame members of a locomotive, and comprising a box-shaped structure having a portion narrowed transversely to provide oppositely disposed spaces for lateral motion device levers, said transversely narrowed portion being thickened vertically to add strength to compensate for loss in strength caused by said narrowing of the casting; and supports in said spaces for said lateral motion device levers carried by said casting.

3. In a structure of the character described, the combination of a cross-tie member made as an integral casting having means for securing it to the side frame members of a locomotive, and comprising a box-shaped structure having a portion narrowed transversely to provide oppositely disposed spaces, said transversely narrowed portion being thickened vertically to add strength to compensate for loss in strength caused by said narrowing of the casting; means on the opposite sides of said casting member at said narrowed portion for supporting lateral motion device levers; and lateral motion device levers in said spaces, carried by said supporting means.

4. In a structure of the character described, the combination of a cross tie member made as an integral casting having means for securing it to the side frame members of a locomotive, and comprising a box-shaped structure having a portion narrowed transversely to provide oppositely disposed spaces for lateral motion device levers, said transversely narrowed portion being thickened vertically to add strength to compensate for loss in strength caused by said narrowing of the casting; supports in said spaces for said lateral motion device levers, carried by said casting; and stops in said spaces for said lateral motion device levers, carried by said casting.

JAMES G. BLUNT.
